United States Patent

Des. 238,671

Patented Feb. 3, 1976

238,671

SPRAY NOZZLE

Edwin C. Rosenberger, Piqua, and Jerome A. Waker,
Troy, Ohio, assignors to Chem-Lawn Corporation,
Dublin, Ohio

Filed June 9, 1975, Ser. No. 584,848

Term of patent 14 years

Int. Cl. D23—01

U.S. Cl. D23—35

FIG. 1

FIG. 2

FIG. 5

FIG. 1 is a perspective view of a spray nozzle showing our new design;

FIG. 2 is a side elevational view;

FIG. 3 is a front end view;

FIG. 4 is a rear end view; and

FIG. 5 is a cross sectional view taken on line 5—5 of FIG. 4.

We claim:

The ornamental design for a spray nozzle, substantially as shown.
